UNITED STATES PATENT OFFICE.

AXEL W. NILSSON, OF PORT WASHINGTON, NEW YORK.

DESIGN FOR TILING.

No. 40,202.

Specification for Design.

Patented Aug. 3, 1909.

Application filed May 17, 1909. Serial No. 496,669. Term of patent 14 years.

To all whom it may concern:

Be it known that I, AXEL W. NILSSON, a citizen of the United States, residing at Port Washington, in the county of Nassau and State of New York, have invented a new, original, and ornamental Design for Tiling, shown in the accompanying drawing.

The figure in the drawing shows the design of the tiling.

What I claim is:

The ornamental design for tiling as shown.

AXEL W. NILSSON.
